UNITED STATES PATENT OFFICE.

JOHN C. WEIS, OF PEORIA, ILLINOIS.

DESIGN FOR A MEDALLION.

SPECIFICATION forming part of Design No. 34,432, dated April 30, 1901.

Application filed March 5, 1901. Serial No. 49,976. Term of patent 14 years.

To all whom it may concern:

Be it known that I, JOHN C. WEIS, a citizen of the United States, residing at Peoria, in the county of Peoria and State of Illinois, have 5 invented and produced a new and original Design for a Medallion; and I do hereby declare that the following is a full, clear, and exact description of the invention, which will enable others skilled in the art to which it appertains to make and use the same.

My present invention relates to a new and original Masonic design for a medallion, which may be understood from the following specification, reference being had to the accompanying drawings, wherein—

Figure 1 is a view showing the face or obverse side of the medallion, and Fig. 2 is a view of the reverse side thereof.

The medallion A is round in form and has 20 a border-line B concentric with and near its outer edge. On the obverse side is represented a twenty-four-inch gage C, placed near what I shall term the "top" of the medallion. Said gage is shown slightly open 25 and forms in this position a Z-shaped figure. At one end of the gage is a plumb D, which is interwoven therewith. Near the other end thereof is a level E, also interwoven, both

plumb and level occupying upright positions. A gavel F is shown hanging head down at 30 the middle of the gage, and from the said head a square G is hung. Between the depending extremities of the square is a trowel H, the point of which passes under one extremity and its handle across the opposite 35 one. The limbs of the gage and square are subdivided into equal parts, that of the gage consisting of eight divisions. The reverse side of the medallion is provided with a border-line I, similar to B on the obverse 40 side, and near the bottom is represented a square and a compass, which interlock. This side is divided into three zones J K L, the lower one, L, containing said square and compass.

Having thus described my invention, I claim—

The design for a medallion as herein described and shown.

In testimony whereof I affix my signature 50 in presence of two witnesses.

JOHN C. WEIS.
